CLAIM

The ornamental design for eyewear, as shown and described.

DESCRIPTION

FIG. 1 is a front perspective view of eyewear;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken line showing of the eyewear is for the purpose of illustrating portions of the article and forms no part of the claimed design. Certain broken lines that form no part of the claimed design merge with solid lines that do form part of the claimed design. The dash-dot lines delineate boundaries between the broken lines and solid lines that merge.
